UNITED STATES PATENT OFFICE.

ADAM BOECHER, OF NEW YORK, N. Y.

MECHANICAL MOVEMENT.

SPECIFICATION forming part of Letters Patent No. 272,200, dated February 13, 1883.

Application filed December 27, 1882. (No model.)

To all whom it may concern:

Be it known that I, ADAM BOECHER, a citizen of the United States, residing at New York, in the county and State of New York, have invented new and useful Improvements 5 in Mechanical Movements, of which the following is a specification.

This invention relates to mechanical movements for converting continuous rotary motion 10 into oscillating or rotary reciprocating motion; and it consists in the combination of a rock-shaft having a fixed wheel or arm, an eccentric having a suitable pitman, a link connecting said pitman to the wheel of the rock-shaft, and a guide for the pitman, as herein-after more fully set forth.

This invention is illustrated in the accompanying drawings, in which—

Figure 1 is a side elevation, showing the 20 parts in one extreme position. Fig. 2 is a similar view, showing the other extreme position of the parts. Fig. 3 illustrates a modification of the guide for the pitman. Fig. 4 shows another modification thereof.

25 Similar letters indicate corresponding parts. The letter A designates the rock-shaft; B, its wheel; C, the eccentric; D, the pitman; E, the link, and F the guide for the pitman, the wheel being fixed to the rock-shaft, and the 30 pitman having a suitable connection with the eccentric, while the link serves to connect the pitman to the wheel, it practically forming a continuation of the pitman.

Instead of the wheel B, an arm may be used. 35 One of the conditions necessary to the successful operation of this movement is that the pin or pivot o, forming the joint between the pitman D and link E, shall be or remain on one side of the vertical plane of the axis of the 40 rock-shaft, in any position of the parts, and to fulfill such condition is the function of the guide F of the pitman. In the example shown in Figs. 1 and 2, said guide F consists of an os-

cillating arm, which is connected at one end to a pivot, s, and at the other end to the pitman, said pivot having a fixed position, and in the example shown in Fig. 3 the guide consists of a stud, which is fitted into a slot, F', formed in the pitman, while in the example shown in Fig. 4 the guide consists of a groove 45 having fitted therein the joint-pin o, the latter being extended at one end for this purpose. When a continuous rotary motion is given to the eccentric C, the wheel B, together with the rock-shaft, obtains a rotary reciprocating 50 motion from the position shown in Fig. 1 to that shown in Fig. 2, and vice versa. The motion of the rock-shaft is over or through an arc of ninety degrees, (more or less,) due to which fact this movement can be used to advantage 55 in sewing-machines for obtaining from the upper or needle-driving shaft the proper motion of the shuttle-shaft; but it is evident that the same can be used for various other purposes to which such motion may be applied.

An important advantage of the movement is, that the link is left free of any intermediate pivotal connections, and the only wearing-points liable to affect the rock-shaft are the pivots at the ends of the link.

What I claim as new, and desire to secure by Letters Patent, is—

The combination, substantially as hereinbefore described, of the rock-shaft having the fixed wheel or arm, the eccentric having a 75 suitable pitman, the link connecting said pitman to the wheel of the rock-shaft, and the guide for the pitman.

In testimony whereof I have hereunto set my hand and seal in the presence of two subscribing witnesses.

ADAM BOECHER. [L. S.]
